CLAIM

The ornamental design for a device for melting glue, as shown and described.

DESCRIPTION

FIG. 1 is a perspective view of a device for melting glue according to our design;

FIG. 2 is a front view of the device for melting glue of FIG. 1;

FIG. 3 is a rear view of the device for melting glue of FIG. 1;

FIG. 4 is a left side view of the device for melting glue of FIG. 1;

FIG. 5 is a right side view of the device for melting glue of FIG. 1;

FIG. 6 is a top view of the device for melting glue of FIG. 1; and,

FIG. 7 is a bottom view of the device for melting glue of FIG. 1.
